UNITED STATES PATENT OFFICE.

JOSEPH T. MANNING AND CHARLES F. CLUDIUS, OF PHILADELPHIA, PENNSYLVANIA,
ASSIGNORS TO LOOMIS-MANNING FILTER MANUFACTURING COMPANY, OF CAMDEN, NEW JERSEY, A CORPORATION OF NEW JERSEY.

APPARATUS FOR SUPPLYING HOT WATER IN HOUSES.

1,377,714.

Specification of Letters Patent. Patented May 10, 1921.

Application filed March 1, 1917. Serial No. 151,832.

To all whom it may concern:

Be it known that we, JOSEPH T. MANNING and CHARLES F. CLUDIUS, both of us citizens of the United States, residing at Philadelphia, in the county of Philadelphia and State of Pennsylvania, have invented certain new and useful Improvements in Apparatus for Supplying Hot Water in Houses, of which the following is a specification.

10 This invention relates to apparatus whereby water which has been heated and then filtered in heated condition can be withdrawn in heated condition promptly upon opening any faucet on a pipe line leading thereto from the filtering appliances.

Heretofore in probably the majority of houses having water systems the apparatus has been such that the water in the hot water pipe line cools off unless one or more open 20 faucets are causing a flow; and hence upon opening a faucet after all faucets have been closed for a considerable time the cooled water must be allowed to run out and the pipe line to fill again before hot water will 25 appear at the faucet. In many houses, however, in order to avoid this defect, the hot water pipe line has been connected with the hot water storage tank (if one should be used) or with the hot water heater (if a hot 30 water storage tank should not be used) by pipe connections in such manner that a circulation of hot water out of and back to the hot water storage tank, or the hot water heater, takes place at least whenever the 35 faucets are all of them closed. The inclusion in such a pipe circuit of appliances for filtering the hot water would ordinarily at least be impracticable; in view of the attendant resistance to flow.

40 In accordance with the present invention in what is considered its most advantageous form, where a hot water storage tank is used, an appropriate part at least of the water heating and hot water storing means 45 is included in an endless pipe circuit (called heater circuit hereinafter) along with a chamber of small cubic contents as compared with the storage tank and in the form of an at least approximately straight pipe; 50 while the pipe line on which the hot water faucets are located is included in another endless pipe circuit (called pipe line cir-

cuit hereinafter) along with a chamber of comparatively small cubic contents and in the form of an at least approximately 55 straight pipe; which latter chamber is arranged relatively to the former for transfer of heat between their respective liquid contents. The water heating and hot water storing means are connected with the inlet 60 of the filtering appliances by pipe connections which may either include a portion of, or be wholly separate from, the said heater circuit. The filtering appliances are connected at their outlet with the said pipe line 65 circuit by appropriate pipe connections.

Thus the tendency of the hot-filtered water to cool off in the pipe line is counteracted by the tendency to transfer heat from water in the heater circuit to that in the 70 pipe line circuit.

Provision should be made for escape of air from each of the heat transferring chambers in order that collection of air therein may not check the flow through the chamber. Most advantageously the air passes from one chamber to the filter, and from the other chamber to the pipe line circuit. This circuit would be vented through the 75 faucets or through some other appropriate 80 outlet or outlets.

Where a hot water storage tank is not used, only water heating means, and not both water heating and hot water storing means, are available for inclusion in the heater circuit, as a whole or in an appropriate part; otherwise the apparatus in what is considered its best form is the same as where 85 a storage tank is used.

Modifications by addition, omission or 90 substitution can be made indefinitely as long as the substance is taken of any one or more of the hereinafter written claims. The accompanying drawings, which illustrate some of the forms which may be adopted, 95 are, therefore, by way of example and do not exhibit all the modifications which would be within the scope of the invention.

Figure 1 is a partly diagrammatic view of one form, mainly in elevation but partly 100 broken away and in section.

Fig. 2 is a detail view.

Figs. 3, 4, 5, 6, 7, 8, 9, 10 and 11 are less complete views of other forms.

Parts not shown in Figs. 3 to 11 and necessary to complete the view can be supplied from Fig. 1 in each case.

Referring to Fig. 1, the water from the street main (or other appropriate source) is supplied through pipe *a* to the lower part of the hot water storage tank *b*. It is heated in the main water heater *c*; which is connected by pipe connections *d* *e* with said tank *b* at different levels. Any appropriate heating agency can be used, as, for example, the fire of a kitchen range or stove or of a furnace, gas flames, steam, electric heating or other agency. Assuming for the present that the pipes *w*, *x* and *y* should be omitted (as they may be) or should be closed by valves, the hot water would flow to chamber *f* by way of pipe connections *g* *g'* and would return more or less lowered in temperature by way of the pipe connection *h*.

Hot water flows to the filter *i* through connections composed of pipes *g* *j* and appropriate passages in filter valve *k*, together with the pipe *l*; which last leads from valve *k* to the inlet end of the filtering appliances. The filter valve *k* and pipe *l* may be like the corresponding parts in Patent 594,640, granted November 30, 1897, to the assignee of the aforesaid Joseph T. Manning. In filtering position the pipes *j* *l* are interconnected through the valve *k*. In this position the outlet end of the filtering appliances is connected by pipe *m* with the pipe line *n* *n'*; on which hot water faucets *p* are located. The connection *g'* allows air to escape from chamber *f* into the pipe *j* leading to the filter.

Faucets are shown on two vertical legs, and also on a horizontal portion of the pipe line; but they may be confined to one vertical leg or be otherwise placed as desired. They may be at such distance from the pipe line as may be desired; and the pipe line can be carried back and forth as desired. The pipe *n'* as shown is connected by branches *n''* with faucet branches *p'* at points near the faucets. This pipe *n'* and its branches *n''* could be omitted, if so preferred; and when it is used all of pipe *n* above the junctions of pipe *n'* therewith could be omitted. Any known or suitable system of pipe line can, in fact, be used. A vent *v'* is shown, which can be opened to allow air to escape from the pipe line *n* *n'* when desired.

The hot water from tank *b* is filtered in heated condition in filter *i*, and passes thence in heated condition through pipe line *n* *n'* to such faucet or faucets *p* as may be open. When the faucets are all of them closed the water in the pipe line *n* circulates through the chamber *g*, which is of small cubic contents as compared with storage tank *c* and in the form of a straight pipe, and which is included in an endless pipe

circuit with said pipe line *n* *n'* by means of appropriate pipe connections, which as shown include flanged unions *r*. In chamber *g* the water is reheated by heat derived from the main heater *c* and transferred by the hot water of the heater circuit. The chamber *f* as shown incloses chamber *g* and is itself comparatively small in cubic contents and in the form of a straight pipe. At each end of chamber *f* is a stuffing box *t*. Air can escape from chamber *g* through right hand union *r* to the pipe line *n* *n'*. When one or more faucets *p* are open the hot water from filter *i* may divide at the coupling *u* and flow part of it each way to the open faucet or faucets; or provision can be made to cause a flow in one direction only, say by an upwardly closing check valve *v*.

By having the vertical legs of the pipe line *n* *n'* of different diameters, the water tends to rise in the pipe of larger diameter; and this tendency can be increased, if desired, by placing on said larger pipe a heat retaining jacket, indicated by the dotted lines 50, leaving the other parts of the pipe line without such protection.

Provision should be made for maintaining the temperature of the water in the filter *i* and other parts intermediate the heater circuit and the pipe line circuit, as, for example, by providing them with heat retaining jackets, indicated by dotted lines 19. Heat retaining jackets can also be provided such other parts, if any, as may be desired. Chamber *f* would ordinarily be provided with a jacket, as indicated by dotted lines 51.

As thus far described, the main heater *c* and storage tank *b* are both of them connected in circuit with the chamber *f* (heater circuit); since the water returning by way of pipe *h* will naturally divide in the bottom of the tank *b* and will rise in part through main heater *c* and in part through tank *b*. If it should be desired for more of the so returning water to pass through main heater *c*, suitable disposition can be made, as, for example, by interconnecting the pipes *h* and *e* by means of the pipe *w*.

Conversely, if it should be desired to lessen the amount of returning water, if any, which should pass through the main heater *c* as forming part of the heater circuit, while including therein an appropriate part of the storage tank *b*, disposition of parts can be made with that end in view; as, for example, by supplying a pipe *x* which would discharge into tank *b* suitably above the level of heater connection *e*. In this arrangement, as in the preceding, the chamber *f* receives water which has been raised in temperature in the main heater *c*.

The pipe connections intermediate the water heating and hot water storing means

b *c* and the filter *i* include in Fig. 1 the pipe *g*; which is a portion also of the heater circuit *e c d b g g' f h*. Such pipe connections can be made more nearly or quite 5 separate from said heater circuit by connecting the chamber *f* with the tank *b* by a pipe *y* with or without omitting connection *g'*. In Fig. 3 connection *g'* is omitted; the pipe between storage tank and filter is 10 marked *j''*; and the chamber *f* in the heater circuit is provided with an air vent *f**.

In Fig. 4 is shown an arrangement for including a larger portion of said heater circuit in the pipe connections between tank 15 and filter. Moreover, the relative positions of the chambers in the heater circuit and the pipe line circuit are shown reversed in this figure, chamber *f'* being inside of chamber *g'*, and the latter carrying stuffing boxes 20 *t*. A reducer *T r'* is shown at left hand end of chamber *f'*. Hot water from tank *b* passes by pipe *g''*, chamber *f'* and pipe *j'* to filter valve *k* (Fig. 1), and leaves chamber *f'* by pipe *h'* for return to tank *b* or 25 heater *c*.

In Fig. 5 the water from tank *b* passes by connection *e* to heater *c*, and thence by pipe 2 to chamber *f*; from which it returns to tank *b* by way of pipe 3 at a point above 30 the level of connection *e*. Pipe *j''* conveys the hot water to filter valve *k* (Fig. 1).

In Fig. 6 the chamber *g''* (included in the pipe line circuit) is inclosed in the hot water storage tank *b*, thus dispensing with 35 a heat transferring chamber in addition to said storage tank and, of course, also with the corresponding pipe connections for including such a chamber in circuit with an appropriate part of the water heating and 40 hot water storing means. Notwithstanding the simplification in this direction, there are advantages, however, in the special heater circuit, exemplified in the apparatus of Figs. 1 to 5.

45 A stuffing box *t'* is shown in Fig. 6 at the upper end of chamber *g''*, where this latter passes through the *T* coupling 4, attached by nipple and flanged collar 6 to the tank *b*. The pipe connection *j'''* leads 50 to the filter valve *k* (Fig. 1).

In Fig. 7 the chamber *g'''* in the pipe line circuit is formed on top of the storage chamber *b'* by placing a dish-shaped partition 55 26 in a tank which includes both chambers. The convex side of this partition may be up or down, as preferred. Stuffing boxes 27 are shown for the water inlet pipe *a* and the filter pipe *j''*, which, passing through the reheating chamber *g'''*, lead directly 60 into and out of the storage chamber *b'*.

Where the main heater is a so-called instantaneous heater using gas as fuel, or is otherwise of sufficient heating capacity to heat the water satisfactorily while flowing 65 to an open faucet or faucets, it may be con-

sidered advisable to dispense with a hot water storage tank. One arrangement for such a case is illustrated in Fig. 8; in which water from the street main or other source is supplied by pipe *a'* to the pipe 7; through 70 which the water returns from chamber *f* to the main heater *c*. The hot water passes from main heater *c* by pipes *g''' g'* to chamber *f*, or by pipes *g''' j* to the filter valve *k* (Fig. 1). 75

In Fig. 9 chambers *g* g*** connected in parallel branches *n* n'''* of the pipe line circuit are shown located in a heater *c*, which may be heated in any appropriate way, as, for example, by gas flames from a 80 burner 8 or by steam in a coil 28 or by both. One or other of the said chambers can be omitted; or both of them can be used. The pipe *j''* leads from heater *c'* to filter valve *k* (Fig. 1). The water from the street main 85 or other source enters heater *c'* through pipe *a''*. Flanged unions are shown at *r*.

The horizontally placed storage tank *b''* of Fig. 10 is supplied with water by pipe *a'''* and is arranged for heating either by 90 steam in coil 29 inside said tank, or by any appropriate agency in an outside heater *c* located at a lower level and connected with tank *b''* by pipes *e' d'*, or by heating means in both forms. In places, for example, 95 where steam is supplied part of the year only, the heater *c* using solid fuel or gas could be utilized when the steam is not available. A thermostatic valve is indicated at 30 for checking the flow of steam 100 into coil 29 from branch 31 of steam supply pipe 32 whenever the water in tank *b''* shall reach a predetermined temperature. A trap for discharging water of condensation is indicated at 33 in the outlet pipe 34 from 105 coil 29. The pipe *j''* leads from tank *b''* to the filter valve *k* (Fig. 1).

The reheating chamber *f''* is connected in circuit with tank *b''* by pipes 35 and 36. Said chamber surrounds not only the chamber *g*, forming part of the pipe line circuit, but also a heater pipe 37 for supplementing or replacing the water circulation in the circuit *b'', 35, f'', 36*. Said heater pipe 37 is shown provided with steam connections 38, 115 39, the former leading from the steam supply pipe 32 and the latter leading to the pipe 34, and also with connections 40, 41 for including said pipe 37 in circuit with the heater *c*. In the connection 38 a thermostatic valve is indicated at 42 for checking the flow of steam into heater pipe 37 whenever the water in chamber 43, which is included in the pipe line circuit, reaches a predetermined temperature. 120

It will, of course, be understood that thermostatic valves can be used wherever desired in any of the illustrated arrangements, or in any other arrangement. 125

In Fig. 11 the water in the pipe line cir- 130

cuit is reheated by the flame of a gas burner 15. The products of combustion therefrom are conducted over the chamber q by a casing 16; which is shown provided at its ends 5 with upright flues 17 and 18 in order to insure a draft downward through casing 16.

Each of the chambers q , q' , q'' , q''' , q^* , q^{**} in the pipe line circuit is of comparatively small cubic contents, and each of them, except chamber q''' in Fig. 7, is in the form of an at least approximately straight pipe. Each of the chambers f , f' , f'' in the heater circuit is likewise of comparatively small cubic contents and in the form of an 15 at least approximately straight pipe. Such chambers have a good area of conducting wall in proportion to cubic contents; and they at the same time interpose little resistance to flow of water in the circuit. Chambers 20 comparatively small in cubic contents and of other forms can be used; and the use even of chambers large enough in cubic contents to serve as storage tanks is not wholly excluded.

25 In all the figures, except Figs. 7 and 9, the water in the chamber of the pipe line circuit and hot fluid whose heat is transferred thereto flow in opposite directions on opposite sides of the same heat conducting wall. 30 This is advantageous; as with equal area of conducting wall it gives a higher temperature to the water in said pipe circuit; but a transfer of heat could be effected between the two fluids while flowing in the same 35 direction; and the transfer, moreover, could be indirect; as if two chambers, for example, were immersed in a conducting liquid in a casing common to both; or as if a circulating liquid should absorb heat through 40 the wall of one chamber from the liquid contents thereof and should impart it to the liquid in the other chamber through the wall of the latter. In Fig. 10 the heating of water in chamber q would be effected by steam 45 in heater pipe 37 indirectly through liquid in the chamber f'' .

By shifting the filter valve k (Fig. 1) the direction of flow of hot water through the filter can be reversed for washing the filtering material. In the washing position of valve k the water passes from the top of filter i to waste through pipe 20. Between the pipes j and m is a valved by-pass 21 for temporarily allowing hot water (when so desired) to pass from the former to the latter pipe without passing through either the filter or a filter valve. Valves can be used wherever desired. The reference numerals 55 indicate each of them a valve; but all the 60 valves shown are not marked.

In some of the hereinafter written claims recital is made of "water heating and hot water storing means" and in others of "water heating means." The omission to recite 65 "hot water storing means" in these latter

claims is intended to make them more inclusive. They thus are intended to cover apparatus which comprises "water heating means" and other elements recited in said claims respectively, whether such apparatus 70 should or should not embody "hot water storing means" also.

In like manner the recital of "pipe connections whereby water from said water heating means is conveyed to the filter 75 inlet" is applicable to connections for conveying the hot water thereto, directly or indirectly, with or without intermediate passage of the same through "hot water storing means."

We claim as our invention or discovery:

1. Apparatus for supplying hot water in houses, comprising the following elements in addition to and in combination with water heating and hot water storing means, a filter, 85 a pipe line, and faucets on said pipe line, namely: a chamber, pipe connections whereby said chamber is included in an endless circuit with an appropriate part at least of said water heating and hot water storing 90 means, a chamber arranged relatively to the former chamber for transfer of heat between their respective liquid contents, pipe connections whereby this latter chamber is included in an endless circuit with said pipe 95 line, pipe connections whereby water from said water heating and hot water storing means is conveyed to the filter inlet, and pipe connections whereby water is conveyed from the filter outlet to said pipe line circuit, substantially as described.

2. Apparatus for supplying hot water in houses, comprising the following elements in addition to and in combination with water heating means, a filter, a pipe line, and faucets on said pipe line, namely: a chamber comparatively small in cubic contents, pipe connections whereby said chamber is included in an endless circuit with an appropriate part at least of said water heating 105 means, a chamber arranged relatively to the former chamber for transfer of heat between their respective liquid contents, pipe connections whereby this latter chamber is included in an endless circuit with said pipe 110 line, pipe connections whereby water from said water heating means is conveyed to the filter inlet, and pipe connections whereby water is conveyed from the filter outlet to said pipe line circuit, substantially as de- 115 scribed.

3. Apparatus for supplying hot water in houses, comprising the following elements in addition to and in combination with water heating and hot water storing means, a filter, 120 a pipe line, and faucets on said pipe line, namely: a chamber comparatively small in cubic contents, pipe connections whereby said chamber is included in an endless circuit with an appropriate part at least of said 125

water heating and hot water storing means, a chamber arranged relatively to the former chamber for transfer of heat between their respective liquid contents, pipe connections 5 whereby this latter chamber is included in an endless circuit with said pipe line, pipe connections whereby water from said water heating and hot water storing means is conveyed to the filter inlet, and pipe connections 10 whereby water is conveyed from the filter outlet to said pipe line circuit, substantially as described.

4. Apparatus for supplying hot water in houses, comprising the following elements 15 in addition to and in combination with water heating means, a filter, a pipe line, and faucets on said pipe line, namely: a chamber, pipe connections whereby said chamber is included in an endless circuit and is arranged 20 to receive water from said water heating means, a chamber comparatively small in cubic contents arranged relatively to the former chamber for transfer of heat between their respective liquid contents, pipe 25 connections whereby this latter chamber is included in an endless circuit with said pipe line, pipe connections whereby water from said water heating means is conveyed to the filter inlet, and pipe connections 30 whereby water is conveyed from the filter outlet to said pipe line circuit, substantially as described.

5. Apparatus for supplying hot water in houses, comprising the following elements 35 in addition to and in combination with water heating means, a filter, a pipe line, and faucets on said pipe line, namely: a chamber comparatively small in cubic contents, pipe 40 connections whereby said chamber is included in an endless circuit and is arranged to receive water from said water heating means, a chamber comparatively small in cubic contents arranged relatively to the former chamber for transfer of heat between 45 their respective liquid contents, pipe connections whereby this latter chamber is included in an endless circuit with said pipe line, pipe connections whereby water from said water heating means is conveyed to the 50 filter inlet, and pipe connections whereby water is conveyed from the filter outlet to said pipe line circuit, substantially as described.

6. Apparatus for supplying hot water in houses, comprising the following elements 55 in addition to and in combination with water heating means, a filter, a pipe line, and faucets on said pipe line, namely: two chambers which are relatively arranged for transfer 60 of heat between their respective liquid contents and one at least of which is comparatively small in cubic contents and in the form of a pipe, pipe connections whereby one of said chambers is included in an end-

less circuit and is arranged to receive water 65 from said water heating means, pipe connections whereby the other of said chambers is included in an endless circuit with said pipe line, pipe connections whereby water from said water heating means is conveyed 70 to the filter inlet, and pipe connections whereby water is conveyed from the filter outlet to said pipe line circuit, substantially as described.

7. Apparatus for supplying hot water in 75 houses, comprising the following elements in addition to and in combination with water heating means, a filter, a pipe line, and faucets on said pipe line, namely: two chambers which are relatively arranged for 80 transfer of heat between their respective liquid contents and one at least of which is comparatively small in cubic contents and in the form of an at least approximately straight pipe, pipe connections whereby one 85 of said chambers is included in an endless circuit and is arranged to receive water from said water heating means, pipe connections whereby the other of said chambers is included in an endless circuit with said 90 pipe line, pipe connections whereby water from said water heating means is conveyed to the filter inlet, and pipe connections whereby water is conveyed from the filter outlet to said pipe line circuit, substantially 95 as described.

8. Apparatus for supplying hot water in houses, comprising the following elements in addition to and in combination with water heating means, a filter, a pipe line, 100 and faucets on said pipe line, namely: a chamber comparatively small in cubic contents arranged for its liquid contents to be heated by transfer of heat thereto from water that has been raised in temperature 105 in said water heating means, pipe connections whereby said chamber is included in an endless circuit with said pipe line, pipe connections whereby water from said water heating means is conveyed to the filter inlet, 110 and pipe connections whereby water is conveyed from the filter outlet to said pipe line circuit, substantially as described.

9. Apparatus for supplying hot water in houses, comprising the following elements 115 in addition to and in combination with water heating means, a filter, a pipe line, and faucets on said pipe line, namely: a chamber comparatively small in cubic contents and in the form of a pipe arranged 120 for its liquid contents to be heated by transfer of heat thereto from water that has been raised in temperature in said water heating means, pipe connections whereby said chamber is included in an endless circuit with 125 said pipe line, pipe connections whereby water from said water heating means is conveyed to the filter inlet, and pipe connec-

tions whereby water is conveyed from the filter outlet to said pipe line circuit, substantially as described.

10. Apparatus for supplying hot water in houses, comprising the following elements in addition to and in combination with water heating means, a filter, a pipe line, and faucets on said pipe line, namely: a chamber comparatively small in cubic contents and 5 in the form of an at least approximately straight pipe arranged for its liquid contents to be heated by transfer of heat there- to from water that has been raised in tem- 10 perature in said water heating means, pipe connections whereby said chamber is included in an endless circuit with said pipe line, pipe connections whereby water from said water heating means is conveyed to the filter inlet, and pipe connections whereby 15 20 water is conveyed from the filter outlet to said pipe line circuit, substantially as described.

11. Apparatus for supplying hot water in houses, comprising the following elements in addition to and in combination with water heating and hot water storing means, 25 a filter, a pipe line, and faucets on said pipe line, namely: a chamber, pipe connections whereby said chamber is connected in an 30 endless circuit through which water raised in temperature by said heating means circulates, a chamber arranged relatively to the former chamber for transfer of heat be- 35 tween their respective liquid contents, pipe connections whereby this latter chamber is included in an endless circuit with said pipe line, pipe connections whereby water from said water heating and hot water storing means is conveyed to the filter inlet, and 40 pipe connections whereby water is conveyed from the filter outlet to said pipe line circuit, the chamber in the endless circuit first mentioned having such connection with the pipe leading to said filter that air from the 45 chamber may pass to said filter through this last mentioned pipe, substantially as de- 50 scribed.

12. Apparatus for supplying hot water in houses, comprising the following elements in addition to and in combination with water heating means, a filter, a pipe line, and faucets on said pipe line, namely: a filter supply pipe for conveying water raised in temperature by said heating means to said 55 filter, a chamber connected in an endless circuit for circulation through said chamber of water raised in temperature by said heat- 60 ing means, which circuit includes a branch on said filter supply pipe serving the double purpose of letting water flow into said chamber from said filter supply pipe and air to pass into the latter from said chamber, a chamber arranged relatively to the former chamber for transfer of heat between their 65 respective liquid contents and connected in

endless circuit with said pipe line, and pipe connections whereby water is conveyed from the filter outlet to said pipe line circuit, substantially as described.

13. Apparatus for supplying hot water in houses, comprising the following elements in addition to and in combination with water heating means, a filter, a pipe line, and faucets on said pipe line, namely: a filter supply pipe for conveying water raised in tem- 70 perature by said heating means to said filter, a chamber connected in an endless circuit for circulation through said chamber of water raised in temperature by said heating means, which circuit includes a branch on said 75 filter supply pipe for letting water into said chamber from said filter supply pipe, a chamber arranged relatively to the former chamber for transfer of heat between their respective liquid contents and connected in 80 an endless circuit with said pipe line, and pipe connections whereby water is conveyed from the filter outlet to said pipe line circuit, substantially as described.

14. Apparatus for supplying hot water in houses, comprising the following elements in addition to and in combination with water heating means, a filter, a pipe line, and faucets on said pipe line, namely: a chamber comparatively small in cubic contents ar- 90 ranged for its liquid contents to be heated, pipe connections whereby said chamber is included in an endless circuit with said pipe line, appliances whereby water, heated by the aid of said water heating means, is con- 95veyed to the filter inlet and is at all times in a heated state when so conveyed, and pipe connections whereby water is conveyed from the filter outlet to said pipe line circuit, substantially as described.

15. Apparatus for supplying hot water in houses, comprising the following elements in addition to and in combination with water heating means, a filter, a pipe line, and faucets on said pipe line, namely: a chamber comparatively small in cubic contents and in the form of a pipe arranged for its liquid contents to be heated, pipe connections whereby said chamber is included in an end- 110 less circuit with said pipe line, appliances whereby water, when heated by the aid of said water heating means, is conveyed to the filter inlet and is at all times in a heated state when so conveyed, and pipe connec- 115 tions whereby water is conveyed from the filter outlet to said pipe line circuit, substantially as described.

16. Apparatus for supplying hot water in houses, comprising the following elements in addition to and in combination with water heating means, a filter, a pipe line, and faucets on said pipe line, namely: a chamber comparatively small in cubic contents and in the form of an at least approximately straight pipe arranged for its liquid con- 125 130

tents to be heated, pipe connections whereby said chamber is included in an endless circuit with said pipe line, appliances whereby water, heated by the aid of said water heating means, is conveyed to the filter inlet and is at all times in a heated state when so conveyed, and pipe connections whereby water is conveyed from the filter outlet to

said pipe line circuit, substantially as described.

10

In testimony whereof we affix our signatures at Philadelphia, Pennsylvania, this 28th day of February, 1917.

JO. T. MANNING.
CHARLES F. CLUDIUS.
